CLAIM

The ornamental design for a scanner for a hand-held inventory data collection device, as shown and described.

DESCRIPTION

FIG. 1 is a perspective view of an embodiment of a scanner for a hand-held inventory data collection device, shown attached to the hand-held inventory data collection device; FIG. 2 is another perspective view of the embodiment, shown detached from the hand-held inventory data collection device and from a top back left corner of the embodiment; FIG. 3 is another perspective view of the embodiment, shown detached from the hand-held inventory data collection device and from a top front right corner of the embodiment; FIG. 4 is a left side elevational view of the embodiment; FIG. 5 is a front side elevational view of the embodiment; FIG. 6 is a right side elevational view of the embodiment; FIG. 7 is a back side elevational view of the embodiment; FIG. 8 is a top side elevational view of the embodiment; and, FIG. 9 is a bottom side elevational view of the embodiment. In the various embodiments, the broken lines are included for the purpose of illustrating portions of the article that form no part of the claimed design for that embodiment.

1 Claim, 5 Drawing Sheets
